UNITED STATES PATENT OFFICE.

JOHN K. FERGUSON, OF PORTLAND, KENTUCKY.

IMPROVEMENT IN STEAM-CONDENSERS.

Specification forming part of Letters Patent No. **56,738**, dated July 31, 1866.

To all whom it may concern:

Be it known that I, JOHN K. FERGUSON, of Portland, in the county of Jefferson and State of Kentucky, have invented certain new and useful Improvements in Steam-Condensers; and I do hereby declare that the following is a full, clear, and exact description of the same, reference being had to the accompanying drawing, and to the letters of reference marked thereon.

In the annexed drawing, making part of this specification, A represents a pipe, which conveys the steam, after it has been used in the cylinder of the engine, to the condensing-cylinder B. The cylinder B may be made of boiler-iron, and is provided at the end at which the pipe A enters it with a water-chamber and a cold-water opening at a. The cold-water chamber connects with a series of cold-water tubes, C C, which said tubes are perforated with a great number of small openings, through which cold water is thrown, in small jets, into the heated steam as it arrives from the engine. The tubes C C run longitudinally and the entire length of the cylinder B, if so desired.

At the opposite end of cylinder B to which the cold water is admitted, and near its bottom, are two valves, D D'. These valves open into a box, E, which said box is provided with a partition, which runs longitudinally of it. This box is subdivided into apartments by means of partitions O and P, one of which, O, runs entirely across the box, while the other, P, only half-way, or to partition F.

G, H, and I represent valves in the chambers of the box, formed by the partitions O and P. L and M represent pipes from force-pumps, one of which enters the box E on one side of partition F, and the other on the other side. The pumps which connect with these pipes L and M act both as draw and force pumps. They draw the condensed steam from the cylinder B into the channel-ways, and force it from them, as will be hereinafter described.

J represents an opening in the partition F. K represents a pipe in the box E, through

which the water and condensed steam is forced from the said box.

In using this condenser the exhaust-steam, as has been stated, is brought through the pipe A to cylinder B, where it is subjected to cold-water spray or jets of cold water from the perforated pipes C C. As the steam is thus condensed, it, with the water which was used for condensing, falls into the bottom of cylinder B, and passes out into box E through valves D and D'.

The two force-pumps, working, force the water on one side of partition F, from chamber x to x'', and then into x''', and thence up the pipe K. The pump on the other side forces the water from chamber x' into x'', and thence up pipe K.

It will thus be seen that a pump is used for each exhaust, and that the channel-ways on each side of partition F are kept from filling.

An opening is made in the top of box E, over each of the chambers in it, so that in case anything becomes deranged with the valves the bonnets or doors of these openings may be removed and the valve set to right.

The number of pipes C will be regulated by the amount of steam to be condensed.

Having thus fully described my invention, what I claim as new, and desire to secure by Letters Patent, is—

1. The cylinder B, provided with a series of perforated pipes, C C, and valves D D', and used with the exhaust-pipe A and cold-water pipe at a, substantially as and for the purpose specified.

2. The box E, provided with a series of chambers and valves, as described, when used with the cylinder B and force-pumps M and L, substantially in the manner and for the purpose set forth.

As evidence that I claim the foregoing I have hereunto set my hand in the presence of two witnesses.

JOHN K. FERGUSON.
